UNITED STATES PATENT OFFICE.

ROBERT McCRUM, OF LONDON, ENGLAND.

LETTER-OPENER.

1,096,933.

Specification of Letters Patent. Patented May 19, 1914.

Application filed February 10, 1911. Serial No. 607,754.

To all whom it may concern:

Be it known that I, ROBERT McCRUM, a citizen of the United States of America, residing at 317 High Holborn, in the county of London, England, have invented new and useful Improvements in Letter-Openers, of which the following is a specification.

This invention relates to machines for opening envelops in which the opening is effected by abrading the edge of the envelop or other covering. Hitherto the fine dust produced by these machines has been the source of some trouble and various means have been devised to render the dust innocuous. According to the present invention there is combined with the machine a fan or air pump which causes air to pass over the abrading surface while at work and carries the dust with it into a suitable collector.

The preferred construction of machine as hereinafter described has an abrading roller arranged to project slightly through an opening in a surface plate. Except for the roller this plate is left absolutely unobstructed so that envelops or packages of any desired size within reason may be opened upon the machine. Preferably an electric motor is provided to operate the machine and this can conveniently be arranged in a casing beneath the surface plate together with the abrading roller. In another part of the same casing is a fan for drawing air past the roller and a filter to collect the dust. It is found unnecessary to mechanically clamp the letters when they are to be opened. In the present construction a guide plate is provided against which the letters are held by hand during the operation while an adjacent guard plate prevents any risk of the hands being brought into contact with the abrading roller. These and other novel and important features of the invention are more particularly described in the following specification.

The accompanying drawings illustrate this preferred construction of machine.

Figure 1 is a cross sectional elevation of the whole machine. Fig. 2 a plan; Fig. 3 a plan with the surface plate removed; Fig. 4 is a detail of the dust collector; Fig. 5 a detail view of the means for adjusting the roller; Figs. 6 and 7 are details of the roller support; Fig. 8 illustrates a feature of the surface and guide plate; Fig. 9 the fixing of one end of the surface plate, and Fig. 10 the casing inclosing the abrading roller.

Fig. 11 is a further detail of the guide plate and surface plate. Fig. 12 is a partial sectional elevation showing certain modifications. Fig. 13 is a detail of the guard plate 60 and surface plate.

As may be seen from Fig. 1 the whole machine comprises a base plate 1 which may be stamped or cast and is preferably provided with rubber feet 2. Upon this base 65 plate is erected a casing 3 preferably also stamped which supports at its top the surface plate 4. This has a perfectly smooth and flat upper surface with no raised edges or other obstructions whatever. For the 70 sake of lightness it is preferably made of aluminium which has the further advantage of not readily corroding. The plate is pivoted by the lugs 5 upon the casing 3. This fixing is seen more clearly in Fig. 9 75 where a stud 6 is shown passing through the casing 3 and into the lug 5. Approximately in the middle of the plate 4 there is an opening through which protrudes the abrading roller 7. This roller is preferably mounted 80 in ball bearings as shown in Figs. 6 and 7, its spindle having a pulley 8 upon it by which it is driven as hereinafter described. The roller may be made of wood and the abrading surface formed upon it by gluing 85 on particles of flint and French bur. The roller is driven by belt 9 from the electric motor 10, the circuit of which is completed through switch 11 to the plug socket 12. Thus the machine may be operated from an 90 ordinary lamp socket by a suitable connection. The remainder of the casing 3 is occupied by a wooden or other box 13 which contains the fan. This fan which is of the centrifugal type comprises a casing 14 in 95 which rotates a shaft 15; to this are secured curved blades 16 to afford access to the fan; the front wall 17 of its box is made as a sliding lid fitting down over the outlet nozzle 18 of the fan. The opening of this nozzle is obstructed by wires 19 which serve to break up the current of air and lessen the noise. If desired there may in addition be a hood 20 covering the opening. Midway in the casing 13 there is arranged a frame 105 21 supporting a sheet 22 of perforated metal and also a sheet 23 of fine silk gauze. This construction is better seen in Fig. 4. It will be understood that the metal plate forms a 110 backing for the gauze through which the air passes, but which obstructs and retains the dust.

It is obviously necessary if full advantage is to be taken of the fan that ingress of air into the casing 13 should be prevented except at the place where dust arises; this is 5 on the incoming edge 24 of the slot through which the roller 7 protrudes and of course on the upper surface of the roller also. Accordingly there is arranged around the roller 7 as seen in Figs. 1 and 10 a casing 25 10 upon the upper edges of which are rubber tubes or other packing 26 adapted to fit against the surface plate 4. If desired the surface plate may be fitted with downwardly projecting flanges 50 covered with felt 51 to 15 provide this dust-tight joint. A pad 27 of felt in the casing 25 fits close against the outgoing surface of the roller 7. This also serves to prevent the dust traveling around with the roller and so gives the fan an opportunity of drawing the dust away. The mouth of the casing 25 is also arranged to 20 fit against the edges of an opening in the box 13, the contacting surfaces being preferably felt covered as indicated at 52 to 25 make a good joint. The box 13 can be slid out from the casing 3 and the surfaces on which it moves are covered with felt 53 to lessen the noise and also to minimize any vibration. Similarly felt stops 54 are 30 provided against which the casing abuts when in position.

For convenience in manipulating the letters there is provided upon the surface plate a frame 28 having members lying along the 35 sides of the plate and a transverse member 29 across the plate. As may be seen from Fig. 11 the plate 4 is provided with a recessed run-way upon which the side members of frame 28 move, there being preferably ball bearing supports 30 interposed. The frame 28 carries a vertical guide plate 31 which is set slanting across the surface 40 plate 4. Beneath the cross bar 29 of the frame 28 there slides a guard plate 32 which 45 also has ball bearings 33 moving upon the run-way in plate 4 (see Fig. 12). This guard plate 32 is provided at its end with a thumb piece 34 and is connected to the frame 28 by a spiral spring 35 (see Fig. 2). The 50 edge of this plate is cut slantwise so as to be parallel with the vertical guide plate 31. The action of spring 35 is to draw the plates together so that the opening between them is diminished. The plate 32 can however, 55 be drawn away and a bunch of letters of desired size inserted between the guide plate 31 and the edge of plate 32. If desired the plate 32 may be locked in a particular position relative to plate 31 by the aid of screw 60 36 passing through the cross member 29. Rubber stops 37 upon the frame 28 serve for the abutment of the supporting members of plate 32. Stops 38 on the pivoted end of the plate 4 (see Fig. 9) serve to prevent the 65 sliding parts 31 and 32 passing off the plate.

altogether. It is convenient, however, that these sliding parts should be held in initial position at the other end of plate 4 to permit of adjustment of the guard plate without movement of the guide plate. For this purpose the frame 28 is provided with beveled surfaces 39 (see Fig. 8) which in the end position engage with leaf springs 40 upon the plate and so frictionally hold the sliding parts in position. 70

In order to adjust the depth of cut of the roller 7 the plate 4 is made adjustable in height. Since it is pivoted at one end the adjustment is conveniently made by the aid of a central screw 41 (see Figs. 1 to 5) 75 which is secured in the casing 3 and abuts upon plate 4. This screw has a suitable nut or milled disk 42 upon it protruding from the casing so that it may be easily turned. Slotted lugs 43 upon the plate 4 engaging 80 over screws 44 in the casing 3 guide the plate and limit its movement; also when the screws 44 are tightened the plate is clamped in its adjusted position, and the selected cut 85 made permanent.

The driving belt 45 for the fan is preferably of round rubber and extends from the pulley on the shaft of motor 10 to the pulley 46 on the shaft of the fan. A similar pulley 47 is mounted close beside 46 but on 90 the casing 3. When the box 13 is to be withdrawn the belt 45 is moved from pulley 46 to pulley 47 so as to leave the fan box 95 free.

In use the surface plate 4 is adjusted so 100 that the abrading roller 7 projects to the desired extent. A number of letters after being shaken to bring their contents to one side are reversed and placed against the guide plate 31, the guard plate 32 being sufficiently withdrawn to permit letters to be thrust against surface plate 4. The letters are then pressed against plate 31, the fingers partly resting on plate 32. These two parts are then moved backward and forward once 105 or twice over the roller which is set in rotation by the motor 10. The edges of the envelop are thus abraded off to an extent depending on the adjustment of the roller and the resulting dust is drawn down through 110 casing 25 into box 13 under the action of the fan 14, 15, 16. The fan draws the air through screen 23 which the dust cannot penetrate. The slight inclination of the screen permits the dust to fall readily particularly on a momentary stoppage of the motor so that choking is hindered. 115

What I claim is:—

1. An envelop opening machine comprising in combination a main framing, an abrasive roller revolvably mounted in said framing, a casing about said roller, a box movable in said main framing and adapted to make joint with the casing about the roller, a dust collector in said box and 120

means in said box for drawing air over the abrasive roller and through the dust collector.

2. In an envelop opening machine the combination of a main framing, a rotatable abrasive roller mounted therein, a surface plate pivoted at one end upon said framing, a screw movable in said framing supporting the other end of said surface plate, and guides projecting from the surface plate over members attached to the frame to guide the plate and limit its motion.

3. In an envelop opening machine the combination of a slotted surface plate, a rotatable abrading roller protruding therethrough, and a horizontal guard plate supported a small distance above and parallel to said surface plate and slideable thereon, said guard plate adapted to support envelopes above the abrading roller.

4. In an envelop opening machine the combination of a surface plate, an abrasive roller protruding therethrough, a vertical plate against which envelopes may be pressed by the thumbs and fingers, and a broad horizontal plate adjacent thereto, said broad horizontal plate forming a finger rest.

5. In an envelop opening machine the combination of a surface plate, an abrasive roller protruding therethrough, a vertical plate against which envelopes may be pressed by the thumbs and fingers, a broad horizontal plate adjacent thereto in position for the fingers to rest upon, means normally drawing said horizontal plate toward the vertical plate, and means for securing the plates in definite relative position.

6. In an envelop opening machine the combination of the main framing, an abrasive roller rotatably mounted therein, a surface plate slotted to permit protrusion of the roller pivoted at one end of the framing, a guide plate sliding on said surface plate, and means at the end of said surface plate operating automatically to frictionally engage the said guide plate and retain it when the surface plate is raised.

7. In an envelop opening machine the combination with a main framing of an abrasive roller rotatably mounted therein, a surface plate slotted to permit protrusion

of said roller, a pad making close joint with said roller on one side thereof, a casing surrounding said roller, means for making joint between said roller and the surface plate, and a dust collector abutting upon the casing surrounding the roller.

8. In an envelop opening machine the combination with an abrasive roller, of a casing about said roller, a box making joint with said casing, a fan in said box, a gauze screen interposed between said fan and said roller, and means for dispersing the air expelled by said fan so as to lessen the noise produced thereby.

9. In an envelop opening machine the combination with a main framing, an abrasive roller rotatably mounted therein, a surface plate slotted to permit protrusion of said roller, a fan removable from said casing, a pulley upon said fan, an electric motor, belts joining said motor to the roller and to the pulley on the fan and a second pulley similar to and adjacent to that upon the fan secured to the framing.

10. In an envelop opening machine the combination of a main casing, a slotted surface plate thereon, an abrasive roller revolvably mounted in said casing and protruding through said slotted surface plate, felt stops and surfaces in said main casing, a box sliding on said surfaces and abutting on said stops, and a fan and dust collector in said box.

11. In an envelop opening machine the combination of a main casing, a slotted surface plate pivoted thereon, an abrasive roller revolvably mounted in said casing and protruding through said surface plate, a casing about said roller, means making close joint between said casing and the surface plate, a fan within the main casing, adapted to draw air over the roller, and a dust collector interposed between said fan and the roller casing.

In testimony whereof I have signed my name to this specification in the presence of two subscribing witnesses.

ROBERT McCRUM.
